CHARLES FERDINAND AUGUST DAHN, OF CALUMET, MICHIGAN.

GRAIN-SHOCKING MACHINE.

1,323,678.

Specification of Letters Patent.

Patented Dec. 2, 1919.

Application filed April 14, 1919. Serial No. 290,054.

To all whom it may concern:

Be it known that I, CHARLES FERDINAND AUGUST DAHN, a citizen of the United States, and resident of Calumet, in the county of

5 Houghton and State of Michigan, have invented certain new and useful Improvements in Grain-Shocking Machines; and I do hereby declare that the following is a full, clear, and exact description thereof.

10 My invention relates to new and useful improvements in machines for depositing bundles of grain in shock relation upon the ground whereby to eliminate the manual shocking operation heretofore necessary in 15 connection with conventional types of grain binders.

It is primarily the object of my invention to provide a machine adapted for connection with a conventional type of grain binder, to 20 travel therewith and to receive bundles of grain as they are discharged from the binder and to discharge said bundles intermittently in upstanding shocks on the ground, coincident with continuous travel of the 25 machine.

It is a more specific and important object of my invention to provide a machine of this character wherein the bundles of grain discharged from the binder are manipulated 30 and set up in shock relation in a manner simulating the manual shocking operation, and avoiding the necessity of tying together the bundles which comprise the shocks.

It is still further my object to provide a 35 machine of this character which is of maximum simplicity consistent with the various essential functions of the parts whereby the machine constitutes a minimum additional draft load in the harvesting operation and 40 wherein a maximum compactness is procured.

A still further object resides in the provision of a machine of this character wherein compensation is had for various irregularities of the ground over which the machine 45 travels, so that the machine may shift in its relation to the binder in accordance with such irregularities without affecting continuous and efficient operation of the machine.

A still further object resides in the provision of a machine of this character wherein in the driving power is procured from the driving mechanism of the binder.

55 A still further object resides in the pro-

vision of a machine wherein the bundles of grain received from the binder are deposited on the ground in mutually inclined rows to form the shocks.

With the above and other objects and advantages in view, which will be apparent as the description proceeds, my invention resides in the novel features of construction, combination and arrangement of parts, as hereinafter described and defined by the 60 appended claims.

In the accompanying drawings:

Figure 1 is a plan view of my improved shocking machine associated with a grain binder, which is shown in conventional outline.

Fig. 2 is a longitudinal vertical sectional view on the line 2—2 of Fig. 1.

Fig. 3 is a horizontal sectional view on the line 3—3 of Fig. 2.

Fig. 4 is a vertical sectional view taken centrally through the turn table of my machine on a plane at right angles to the plane of Fig. 2, as indicated by the line 4—4 of Fig. 1.

Fig. 5 is a detailed view showing the shock release trip member carried by a rim portion of the turn table.

Fig. 6 is a vertical sectional view through the shock carriers in their position depositing the shocks on the ground.

Fig. 7 is a detailed view showing the means for actuating the holding fingers of the shock carriers.

Referring now more particularly to the accompanying drawings, in Figs. 1 and 2 there is shown conventionally a common form of binder including the main frame *a* having transversely journaled therein at one end the pitman shaft *b* over which extends the downwardly inclined discharge table *c* for the bundles. This end portion of the frame is supported by the drive wheel *d*, and has extending therefrom the usual draft tongue *e*.

For attaching my improved shocking machine to the binder, and for deriving power from the shaft *b* for operating the machine, a bracket *10* is secured to the adjacent end sill of the binder frame *a* and has extending outwardly therefrom a tubular bearing *11* in which is disposed a stub shaft section *12* driven from the shaft *b* by intermeshing beveled gears *13*.

My improved shocking machine comprises a base frame including side sills *14* and end

sills 15, the width of the frame adjacent its inner end being reduced. Upstanding from the inner end of the base frame are brackets 16, the upper ends of which are pivotally mounted on pins 17 projecting from a collar 18 journaled on the tubular bracket bearing 11. Thus, a universal connection is afforded between the base frame and the binder permitting tilting movement of the 10 base frame either on its longitudinal axis or on the axis of the pins 17. The outer end of the main frame is supported by ground wheels 19 carried by swiveled forks 20 secured adjacent the outer corners of 15 the frame. Mounted above the base frame is an upper frame including side sills 21 and end sills 22, this upper frame carrying the operating mechanism of the machine, which mechanism includes a longitudinal 20 shaft 23 carried by hanger bearings 24 on the upper frame and having its end adjacent the binder squared for sliding engagement in a sleeve shaft 25 connected by a universal joint 26 with the drive stub shaft 25 12 of the attaching bracket, the axis of this universal joint coinciding with the axis of the pins 17 whereby to permit a free driving action upon vertical tilting movement of the base frame. The upper frame is supported by rollers 27 mounted in hanger brackets on the side sills 21 of said frame, and riding on the sills 14 of the base frame, whereby free relative longitudinal shifting of the frames is permitted. Disposed above 30 the upper frame is a bundle receiving table 28 which is provided adjacent its outer end with a depending arm 29 having its lower portion bifurcated and pivoted on pins 30 projecting radially from a collar 31 which 35 is journaled on a sleeve 32 which is carried by one of the cross sills 22 of the upper frame, and incidentally forms an intermediate bearing for the main drive shaft 23. The platform 28 is thus afforded a universal 40 connection with the upper frame, and the forward end of the platform carries brackets 33 for pivotal connection with the outer end of the discharge table c. The intermediate portion of the forward sill 14 of the 45 base frame is connected with the draft tongue e of the binder by a diagonal brace link 34, and the outer end of the upper frame carries bundle receiving members movable over the table 28.

50 A maximum flexibility of the various parts of my machine is procured by the aforescribed pivotal connections of the various frames and platform parts to compensate for irregularities of the ground over 55 which the machine travels, in such manner as to insure continued efficient operation of the machine, it being noted that tilting movement of the base frame on its longitudinal axis and independently of the binder 60 65 will not affect the position of the table 28.

Also tilting movement of the base frame on the axis of the pins 17 will merely slightly raise or lower the table 28, the upper frame moving longitudinally on the base frame incidental to such tilting movement of the latter. The shock forming members of my machine operate in pairs, each member being adapted to receive a row of bundles from the binder in their horizontal position as discharged from the binder, and to swing the row of bundles to inclined position against a row of bundles gathered and swung by the preceding member.

In carrying out this operation, I provide a turn table base plate 35 mounted on the outer end of the upper frame, which projects past the table 28. This base plate is provided with an upstanding annular track flange 36, and journaled centrally in a bearing on the plate is a vertical shaft 37 carrying a turn table 38 provided with a down-turned peripheral flange 39 located inwardly of the track flange 36.

Vertically journaled in diametrically opposed intermediate portions of the turn table are a pair of shafts 40, each shaft having its upper end bifurcated for pivotal connection with a carrying shaft 41 of one of the shocking members, the shocking members carried by the shaft 41 being designated by the letter A. Shocking members B, each adapted for co-operation with a corresponding shocking member A are mounted on shafts 42 pivoted between pairs of ears 43 upstanding on diametrically opposed intermediate portions of the turn tables, the pivotal connections of the shafts 41 and 42 being preferably equally spaced about the shaft 37. For supporting the shafts in substantially horizontal radially extending position, a hanger bracket 44 is carried by each shaft and mounts a roller 45 which rides on the track flange 36 of the turn table base. The shafts 42 are held in radial position upon rotation of the turn table by upstanding stops 46 on the periphery of the turn table engaging the shafts at their sides which are disposed rearwardly with respect to the direction rotation of the turn table, this direction of rotation being counterclockwise as shown in Fig. 1. The hanger brackets of the shafts 41 and 42 are slideable thereon, and to dispose co-acting shock forming members A and B in parallel relation to each other and to the direction of travel of the machine, when said co-acting shock forming members are disposed rearwardly thereof to discharge the shock, a crank arm 47 is provided on the lower end of each shaft 40 under the turn table, and this arm carries a depending roller 48 which rides in a substantially elliptical cam channel formed by upstanding flanges 49 on the turn table base. At the side of the turn table base adjacent the table 28, the end arc of 130

the channel is concentric with the turn table, while the other end arc of the cam channel is disposed at the opposite side of the turn table axis and has its center spaced outwardly therefrom. Thus, when each of the carrier shafts 41 of the shocks members A is disposed on and adjacent the table 28, it projects radially from the turn table, but as the shaft and shock member move rearwardly of the machine, the crank arm roller 48 riding in the cam channel will swing the shaft 41 in a clockwise direction counter to the opposite bodily movement of the shaft and hence retard the swinging action of the shock forming member A. As shown more particularly in Fig. 1, by this arrangement a movement of the turn table and consequently of the pivot shaft 40 of each carrier shaft 41 through an arc of 180° will swing the shock forming member A through an arc of 90°, at the same time shifting said member outwardly of the machine to lie at one side of the turn table axis. Thus, upon successive quarter revolutions of the turn table, a shock forming member A may be disposed on the table 28 to fill said member with bundles, then shifted to dispose a shock forming member B on the table to receive its load of bundles and finally upon shifting the member B to lie in rearward discharging position, the shock forming member A will be disposed in parallelism therewith whereby the rows of bundles carried by the members may rest against each other upon withdrawing the members, to thus form the shock.

Each of the shock forming members A and B comprises an elongated head plate 50 which is provided at one side of its center with a collar 51 mounted on an elongated sleeve 52 slidably mounted upon the carrying shaft 41 or 42. The sleeve 52 engages in and is secured in the upper sleeved end of the hanger bracket 44, and the collar 51 of the head plate is held against movement on the sleeve by confinement between said bracket and a collar 53 fixed on the sleeve at the opposite side of the plate. Extending from each side portion of the head plate 50 are a series of tines 54 forming a skeleton container for a row of bundles. The outer ends of these tines are flared to facilitate the insertion of bundles between the series, and it is noted that the carrying shaft of the shock forming member is extended to form one of the tines. The shock forming member is adapted to rest on the table 28 as shown in Fig. 2, to receive bundles directly from the discharge table c of the binder, and a bar 55 extends transversely over the inner end portion of the table to support the upper series of tines 54, the ends of the bar being extended outwardly of the sides of the table and then bent downwardly and inwardly at 56 for attachment to the table whereby to provide ample clearance for the ends of the bundles in moving therewith. To provide an inclined relation of the bundles whereby to facilitate their support on the ground when they are moved to shock forming position, a sinuously bent wire 57 extends between the series of tines at their inner end portions and is disposed obliquely with respect to the head plate 50. To render this stop member adjustable whereby to vary the inclination imparted to the end bundles of the row deposited in the shock forming member, one end thereof is pivoted at 58 to the base portion of one of the tines, and its other end has formed thereon a loose collar 59 receiving an opposite end tine, and adjustably secured thereto by a set screw 60. Bundles of grain are fed into the shock forming member from the discharge table c of the binder by kicker arms 61 which work in longitudinal slots formed in the inner end portions of the table 28 and which have their lower ends pivoted to links 62 carried on a shaft 63 mounted transversely in the side sills 21 of the upper frame. A crank shaft 64 is journaled on said sills and has its crank portions engaged in intermediate bearings of the kicker arms, whereby a conventional feeding movement may be imparted to the kicker arms by rotation of the shaft, to positively force the bundles between the series of tines 54. The shaft 64 is driven by a sprocket connection 65 with a stub shaft 66 having intermeshing beveled gear connection 67 with the main drive shaft 23.

To hold a row of bundles within the shock forming member until the row of bundles are moved to a desired release position, a shaft 68 is transversely carried by the outer end portions of each series of tines of the members A and B which is disposed upwardly when the member is on the loading table 28. This shaft is journaled in bearings 69 on said tines, and is inclined inwardly in a general manner corresponding to the inclination of the stop 57 whereby in conjunction with said stop to compress the head end portions of the row of bundles. The shaft 68 carries a series of radial fingers 70 which are adapted to extend transversely across the mouth of the container defined by the tines. These fingers are normally held in retracted position by a spring 71 secured at one end to the base portion of one of the tines and having its other end secured to the link 72 which is connected with a crank arm 73 on the shaft. This link is also connected with a lever 74 pivoted adjacent its lower end to the head plate 50 of the shock forming member, and said lever carries an angular rock finger 75 which is engageable with a cam 76 projecting from the outer end of the table whereby to rock the lever upon movement of the shock forming member.

ing member from the table and to consequently swing the holding fingers 70 transversely between the tines. The lever is held in this position by a latch finger 77 resiliently urged theretoward by a spring 78, and thus bundles are held within the shock forming member, against movement therefrom in the direction of the tines until the latch finger 77 is released.

10 To impart intermittent quarter revolutions to the turn table, which are so timed as to permit the filling of successive shock forming members between such movements, a beveled gear wheel 79 is loosely mounted 15 on the lower end of the turn table shaft 37, which projects below the base plate 35, and this gear wheel meshes with a beveled pinion 80 on the end of the main drive shaft 23. The gear wheel 79 carries clutch teeth 20 engageable with the teeth of a clutch member 81 splined on the shaft 37, and movement of this clutch member is controlled by loose engagement therewith of the branched intermediate portion of a lever 82 having one 25 end pivoted to the base plate 35. The other end of the lever is resiliently urged to ride upon the upper face of an annular cam rib 83 mounted on the gear wheel, and this cam rib has a depressed portion extending 30 through one quarter of its periphery whereby when the lever rides on said depressed portion, the clutch member 81 will engage the teeth of the gear wheel 79 to procure driving operation of the turn table, and 35 whereby when the lever rides upon the major raised portion of the cam surface, the turn table will be idle with one of the shock forming members halted upon the table 28 to receive its load of bundles, and since the 40 stationary intervals of the turn table are three-fold greater in length than the rotating intervals, sufficient time will be afforded for loading the bundle forming members.

45 The collars of the head plates 50 form pivot bearings therefor, and by reason of the disposition of said collars laterally of the centers of the plates, said plates and the container structures carried thereby are overbalanced at their sides which receive the 50 base ends of the bundles. Thus, as the shock forming members A and B move from the table 28, the container structures will swing on the sleeves 52 to procure a substantially vertical position of the row of bundles carried thereby, so that the bases of the bundles rest on the ground in the rearward position 55 of the shock forming members. When the shock forming members A and B are disposed in parallel rearward relation as shown 60 in Fig. 1, a mutual inclination of the rows of bundles is procured by a lateral abutment 84 on one of the head plates 50 which engages the other head plate below the pivotal axis of the head plates to thus procure the 65 relation shown in Fig. 6.

It is necessary for the shock forming members A to move past their rearward limit of movement without releasing the holding fingers 70 of the rows of bundles carried thereby, so that the bundles are held 70 until such time as the coacting shock forming member B moves to rearward position, so that both rows may be simultaneously released to procure their mutual support. To procure this simultaneous release, the 75 track flange 36 of the base plate 35 is cut away at its rear portion, and a shiftable track section 85 is provided which is carried by a plate 86 slideable in guides 87 mounted under the base plate, this shiftable track 80 section being adapted to lie in the cutaway portion to form a continuation of the track flange, and being shiftable rearwardly. The track section is normally held in registry with the track flange 36 by an intermediate 85 pivoted latch lever 88 which has one end engageable with a stop 89 carried on a pin upstanding from the plate 86 and slideable in a radial slot 90 of the base plate, the latch lever being resiliently urged to this 90 position by a lever spring 91. A trip bar 92 is disposed under and rearwardly of the base plate 36, the end portions of this bar being extended downwardly and then inwardly for attachment to the base plate to 95 provide clearance for the end of a release arm 93 connected with each latch finger 78, which as heretofore explained controls the operative position of the holding fingers 70 of the shock forming members. Formed on 100 the inner periphery of the depending flange 39 of the turn table adjacent each shock forming member B is a cam projection 94 engageable with the lever 88 to trip said lever and release the plate 86 and track section 85 carried thereby for outward movement. This release is timed to occur when the supporting wheels 45 of both shock forming 105 members A and B are on the track section. Thus, when the lever 88 is tripped, the shock forming members remain stationary for a brief period, and the advance of the machine engages the trip bar 92 with the arms 93 to release the latch fingers 78 and consequently release the holding fingers 70. 110 The shock forming members are thus free to strip from the rows of shocks carried thereby, which rows of shocks being inclined together in all directions are afforded mutual support to retain their standing position forming the shock. To return the track section 85 to alignment with the track flange portions 36 whereby upon succeeding 115 rotative movement of the turn table, the rollers 45 will ride on the track flange, an abutment finger 95 depends from the plate 86, and this abutment finger is engageable by the upturned arm of an angle lever 96 which is pivoted on a bracket 97 depending 120 from the base plate 35 and which is rocked 125 from the base plate 35 and which is rocked 130

by engagement of its other arm with a cam projection on the under face of the drive gear wheel 79. This cam projection is located immediately in advance of the depressed portion of the cam rib 83 with respect to the direction of rotation of the gear wheel, and it is noted that in alternate rotations of the gear wheel, the lever 96 would be rocked idly by the cam. As the shock forming members travel around the front of the turn table, they are rocked to horizontal position for engagement on the loading table 28 by means of a downwardly inclined lifting extension 99 of said table. It is noted that the height of the table 28 is substantially equal to the distance between the pivotal axes of the shock forming members and the ground so that when the members are swung to vertical position, the bases of the bundles carried therein will rest against the ground, the height of the table being thus about three feet in a machine designed for harvesting wheat and similar grains.

25 An exceedingly simple and compact machine has thus been provided which will receive bundles from a conventional binder and deposit said bundles on the ground in proper shocks, and in an entirely automatic manner to thus dispense with the element of manual labor heretofore found necessary in completing the work of the binder.

What is claimed is:

1. A grain shocking machine including a wheeled base frame, means for universally pivotally connecting said frame with a grain binder, a table having slidable connection with the main frame, means for pivotally connecting the table with the discharge table of the grain binder, and means carried by the main frame for moving bundles from the first named table and depositing said bundles in shocked relation on the ground.

2. A grain shocking machine including a base frame, means for universally pivotally connecting the base frame with a grain binder, a second frame slidably mounted on the base frame, a table, a single support for said table universally pivoted on the second frame, means for pivotally connecting the table with the discharge table of the grain binder, and means carried by the second frame for moving bundles from the first named table and depositing said bundles in shocked relation on the ground.

3. A grain shocking machine including a base frame, means for universally pivotally connecting the base frame with a grain binder, a second frame slidably mounted on the base frame, a table, a single support for said table universally pivoted on the second frame, means for pivotally connecting the table with the discharge table of the grain binder, a turn table mounted on the second named frame, and shock forming

members carried by the turn table and movable over the first named table.

4. A grain shocking machine including a main frame, a tubular bearing bracket adapted for securement to a grain binder, a stub shaft journaled in said bearing bracket and adapted to be driven from the grain binder, a collar journaled on the tubular bearing, pintles on said collar, brackets on the main frame journaled on said pintles, an extensible shaft line in universal connection with said stub shaft, and means mounted on the main frame and operable by said shaft line for receiving bundles discharged from the binder and depositing said bundles on the ground in shocked relation.

5. A grain shocking machine including a main frame, a tubular bearing bracket adapted for securement to a grain binder, a stub shaft journaled in said bearing bracket and adapted to be driven from the grain binder, a collar journaled on the tubular bearing, pintles on said collar, brackets on the main frame journaled on said pintles, a second frame slidably mounted on the main frame, a longitudinal shaft carried by said frame and having universal connection with the stub shaft, a loading table, a depending arm on the loading table having universal connection with the second frame co-axial with the shaft thereof, means for pivotally connecting said table with the discharge table of the grain binder, and means carried by the second frame and operable by said shaft thereof for moving bundles from the loading table and discharging them in shocked relation on the ground.

6. A grain shocking machine including a plurality of shock forming members, means for successively charging said shock forming members with rows of bundles, and means for moving pairs of said members to parallel position whereby to dispose rows of bundles carried thereby in shocked relation.

7. A grain shocking machine comprising a substantially horizontal table adapted to receive bundles from a grain binder, a series of shock forming members, means for moving said members successively over the table to receive rows of bundles therefrom, means for disposing pairs of said shock forming members in parallel relation at the rear of the machine, and means for releasing rows of bundles from the shock forming members when disposed in such parallel position.

8. A grain shocking machine comprising a turn table, a loading table, radial shafts carried by the turn table and movable over the loading table, shock forming members pivoted on said shafts and normally disposed in vertical position, means for swinging said shock forming members to horizontal position on the loading table, means for imparting intermittent rotative steps to the

turn table, and means for disposing pairs of said radial shafts in substantially parallel relation at the rear of the machine.

9. A grain shocking machine including a loading table, a turn table, pairs of co-acting shock forming members carried by the turn table and movable successively over the loading table, means for imparting rotative steps to the turn table, means for retarding swinging movement of one shock forming member of each pair upon rotation of the turn table whereby to dispose said member in parallel relation to the succeeding member of the pair, and means for releasing bundles from said shock forming members when disposed in such parallel relation.

10. A grain shocking machine including a loading table, a turn table, pairs of co-acting shock forming members carried by the turn table and movable successively over the loading table, means for imparting rotative steps to the turn table, means for retarding swinging movement of one shock forming member of each pair upon rotation of the

turn table whereby to dispose said member in parallel relation to the succeeding member of the pair, means for holding bundles in said shock forming members and means including trips carried by the turn table for releasing bundles from both shock forming members when disposed in such parallel relation.

11. A grain shocking machine including a turn table, a plurality of shock forming members carried by the turn table, means for loading rows of bundles into successive shock forming members upon rotation of the turn table, means for disposing pairs of shock forming members in parallel relation at the rear of the machine, and means for releasing bundles from said shock forming members when disposed in such parallel relation.

In testimony that I claim the foregoing I have hereunto set my hand at Calumet, in the county of Houghton and State of Michigan.

CHARLES FERDINAND AUGUST DAHN.
